UNITED STATES PATENT OFFICE.

CHARLES B. SCHROEDER, OF CHICAGO, ILLINOIS.

PATCH-POCKET FOLDER.

1,146,820.

Specification of Letters Patent.

Patented July 20, 1915.

Application filed December 7, 1914. Serial No. 875,845.

To all whom it may concern:

Be it known that I, CHARLES B. SCHROEDER, a citizen of the United States of America, and a resident of Chicago, county of Cook, 5 and State of Illinois, have invented certain new and useful Improvements in Patch-Pocket Folders, of which the following is a specification.

The main objects of this invention are to 10 provide a device for use in apparel making, designed to facilitate the operation of forming or folding the hems on patch pockets, pocket flaps, etc., and to provide a device of this nature requiring no mechanism for 15 its operation and which is reversible to form like pockets for each side of a coat.

These objects are accomplished by the device shown in the accompanying drawings, in which—

20 Figure 1 is a perspective view of a pocket forming device constructed according to this invention. Fig. 2 is another perspective view. Fig. 3 is a view similar to Fig. 2, but shows the reverse side of the device as 25 employed in forming a pocket reverse in form to that shown in Fig. 2. Fig. 4 is a sectional view taken on the line A—A of Fig. 2, showing a patch pocket and its lining with the edges ironed over. Fig. 5 30 is a detail view of a pocket with a lining partly trimmed applied thereto.

The work in forming patch pockets which is facilitated by the present device, heretofore was accomplished solely by hand. The 35 patch pockets were first cut to the desired form and then their edges folded inwardly, basted or hemmed, and ironed before being applied to a garment. With the present device, no careful hand work is required, nor 40 is it necessary to baste the hem before applying the pocket to the garment.

Machines have been provided for somewhat analogous purposes, viz., the folding of collars, neck ties, shirt tabs, etc., but such 45 machines are not reversible in operation to fold the edges of reversely shaped pieces, and are comparatively expensive so as to be impractical for the average coat maker.

The present invention consists of a sheet 50 metal plate 1 such as galvanized iron, or other material having only moderate heat conducting qualities, and a second plate 2 hinged to the plate 1. Plate 1 is provided with an opening 3 slightly larger, but of 55 the same form as plate 2, and the latter may be swung through said opening in

either direction around its hinge connections 4 with plate 1. The device is preferably provided with a handle 5 which may be insulated from plate 1 if desired. The handle is important, since the device becomes heated through the repeated applications of a hot iron in the process of folding the edges of the cloth. The hinged plate 2 may be formed by sawing or cutting a slot 6 or 60 punching out the opening 3 in plate 1. There should be enough clearance between the adjacent edges of the plates 1 and 2 to provide room for the cloth.

In the operation of the device, patch 70 pockets 7 which have previously been cut with or without their lining 8 to the desired size to provide for infolded edges, are placed on plate 1 over the opening 3, as indicated by dotted lines in Fig. 2. The 75 hinged plate 2 is then forced downwardly into the opening 3 so as to lie flush with the surface of plate 1. This causes the edges of the pocket to be turned upwardly, as shown in Fig. 3. The edges are then 80 ironed inwardly, thus completing the pocket, which may then be removed from the device and applied to a coat without necessitating stitching or hemming the pocket before it is sewed to the coat. The device is 85 of special utility in forming velvet pockets, since it protects the face of the pocket from injury in the ironing operation.

The lining may be applied to pockets 90 after their edges are infolded by placing it on the inside of the pocket, and ironing or sewing it to the pocket and then trimming the edges of the lining as shown in Fig. 5. In this manner of applying the lining it is preferably first sewed to the upper edge 95 of the pocket in forming the welt.

Although but one specific embodiment of this invention has been herein shown and described, it will be understood that numerous details of the construction shown may 100 be altered or omitted without departing from the spirit of this invention as defined by the following claims.

I claim:

1. A patch pocket forming device, comprising a metal plate having an opening therein, and a plate hinged to said first mentioned plate at one of the edges of said opening, said hinged plate having an outline corresponding to the outline of said opening but of such size that it may pass through said opening around its hinges. 105 110

2. A patch pocket forming device, comprising a metal plate having a cut out portion in the form of a pocket and a second plate hinged to said first mentioned metal plate in the form of and adapted to fit within said cut out portion.

Signed at Chicago this 4th day of December 1914.

CHARLES B. SCHROEDER.
